UNITED STATES PATENT OFFICE

EMIL L. MUELLER, OF RUTHERFORD, NEW JERSEY

QUICK-CHANGE ELECTRO-HOLDER FOR PRINTING MACHINES

Application filed July 30, 1930. Serial No. 471,728.

This invention relates to a quick-change electro-holder for printing machines, and an object of the invention is to provide a printing machine embodying simple and practical means to facilitate the rapid and easy exchange of electros therein.

A more detailed object is to provide electro-retaining means manually operable to quickly and easily release an electro and to as quickly and easily grip and hold another electro substituted for the first, repeatedly as often as may be desired.

A further object is to so construct the device that it may be controlled by movement of an operator's foot, thus leaving the operator's hands free to manipulate the various elements of the printing machine including the removal and renewal of electros.

Other objects and aims of the invention, more or less specific than those referred to above, will be in part obvious and in part pointed out in the course of the following description of the elements, combinations, arrangements of parts and applications of principles constituting the invention; and the scope of protection contemplated will be indicated in the appended claims.

In the accompanying drawing which is to be taken as a part of this specification, and in which I have shown merely a preferred form of embodiment of the invention:

Fig. 1 is a top plan view of a portion of a printing machine having an electro-holding device therein constructed in accordance with this invention.

Fig. 2 is a vertical sectional view substantially upon the plane of line II—II of Fig. 1, and

Fig. 3 is an enlarged detail sectional view upon the plane of line III—III of Fig. 1.

Referring to the drawing for describing in detail the structure which is illustrated therein, the reference character L indicates a main bed or table top, carried upon suitable supporting legs 1 and supporting a resilient

platen roll 2 which in the instance illustrated is movable in a horizontal plane along racks 3, the roller 2 having gear teeth 4 which ride upon the racks.

The reference character G indicates an electro having printing characters as 5 formed upon its upper face in the usual manner adapted for printing upon the under-surface of a sheet of paper as 6 laid thereon and pressed against the characters by the roll 2.

The roll 2 travels along the racks 3 from a position over the electro to a position at one side of the electro so that when the roller is not in printing position the electro is exposed and is accessible to the operator for removal.

The electro as illustrated consists of a rectangular flat sheet of metal having the characters 5 at its upper surface. Its opposite longitudinal marginal edges as at 7 and 8 are beveled and it rests flat upon the upper surface of a supporting plate 9 which is made up as a part of, or is fixed to, the bed L. A stop strip 10 is provided at one edge of the plate 9 having its edge surface as at 11, beveled to mate the bevel of the edge 6 of the electro, the bevel of said strip being in the form of an under-cut so that the edge of the electro will project beneath a relatively overhanging portion of the strip.

Carried by the supporting plate is a clamp member 12 mounted to slide along the upper surface of the plate toward and away from the strip 10. The member 12 is beveled at its edge facing the strip 10, as at 13, the bevel being opposite to the bevel of the edge 11 of strip 10 and mates the bevel of the edge 8 of the electro so that it provides a portion relatively overhanging a portion of the electro to thereby co-operate with the strip 10 for providing in effect an under-cut groove within which the electro is engaged when the clamp member is pressed against the electro.

The member 12 is connected with a slide rod 14 which is movable longitudinally with

in a bore 15 provided to receive it within the supporting plate 9. This slide rod projects beyond the plate 9 and carries a compression spring 16 one end of which presses against an edge surface as 17 of the supporting plate and the opposite end of which presses against a collar 18 formed upon the rod. The spring 16 is thus arranged for urging the clamp member 12 always toward clamping position against the electro.

There may be only one clamp member 12 if desired, but preferably two or more such clamp members are employed, as illustrated, each having operating parts connected thereto as just described.

At a point beyond the collar 18 each of the slide rods 14 has a stiff link as 19 pivotally connected thereto as at 20. These links have their opposite ends pivotally connected to a pair of rocker arms 21 as at 22 which are fixed upon a rock shaft 23 oscillatably mounted in bearings 24 carried by the main frame. An arm 25 projects laterally from the shaft 23 and has a stiff link as 26 pivotally connected thereto as at 27. The opposite end of link 26 is pivotally connected as at 28 to one arm of a bell crank lever 29 which is oscillatably mounted upon a shaft 30 carried by the bed or table frame L. The opposite arm of the bell crank lever has pivoted thereto as at 31 a stiff link 32 which extends into pivotal connection as at 33 with a foot lever 34. The lever 34 is pivotally mounted upon a carrying shaft 35.

This linkage mechanism provides a simple and practical means whereby the foot lever 34 is adapted for moving the clamp members 12 simultaneously out of gripping engagement against the electro at any moment desired by the operator.

A slight pressure of the operator's foot against the lever 34 will counter-act the pressure of springs 16 and release the electro so that the operator, with his hands, may lift the electro away and substitute another therefor before releasing the foot lever. Release of the foot lever will enable the springs to again move the clamp members 12 to clamping position. And this removal of one electro, and the substitution of another in its place, may be effected very rapidly and as frequently as may be desired by the operator.

The device as thus constructed is admirably adapted for use in instances where only one copy, or a very few copies are to be made off each electro.

As a convenient means by which to adjust the mechanism for co-operation with electros of different sizes it is suggested that the clamp members 12 may be adjustably connected with the slide rods 14 so as to be capable of being held in any selected one of a number of different predetermined positions lengthwise of said slide rods. The

clamp members 12 may be connected with the slide rods for instance by screws as 36 which extend through holes 37 in the clamp members and which are threaded into holes as 38 provided spaced apart along the length of the slide rods. The screws may extend through any selected pair of the holes 37 and many be engaged within any selected pair of the holes 38, according to the position desired for the clamp members longitudinally of the slide rods.

It is noted that while the provision of beveled edges upon the electro, and of relatively under-cut beveled edges upon the strip 10 and clamp members is desirable in most instances, yet the edges of the electro and of the strip 10 and of the clamp members may be formed without a bevel or under-cut if desired, in which instance the strip 10 will constitute a simple stationary shoulder upon the supporting plate, and the clamp members will constitute simple spring pressed shoulders, the opposing faces of the stationary and spring pressed shoulders being parallel to each other or otherwise as may be preferred.

Any appropriate means may be employed for insuring that both or all of the clamp members 12 shall be sure to move into proper tight engagement with the electro whenever the foot lever is released. In the structure herein illustrated this is accomplished by providing a loose connection between the links 19 and their operating arms 21, as through the medium of the slots 39 shown.

As many changes could be made in this construction without departing from the scope of the invention as defined in the following claims, it is intended that all matter contained in the above description, or shown in the accompanying drawing, shall be interpreted as illustrative only and not in a limiting sense.

Having thus described my invention, what I claim as new and desire to secure by Letters Patent is:—

1. In a quick-change electro-holder for printing machines an electro-supporting plate having a flat surface upon which the electro may rest, said supporting plate also having a shoulder thereon against which an edge of the electro may engage, a clamp member movable toward and away from said shoulder, said clamp member providing a second shoulder in opposed relation to the first shoulder and adapted to engage an opposite edge of the electro, a slide rod slidably carried by the supporting plate, said slide rod having a series of threaded apertures therein spaced apart longitudinally thereof selectively usable for the attachment of the clamp member to said slide rod, screws engageable in selected apertures of the rod to thereby fix the clamp member in a selected position of adjustment longitudinally of the

rod, and means manually operable to move the slide rod.

2. In a quick-change electro-holder for printing machines, an electro-supporting plate having a flat surface upon which the electro may rest, said supporting plate also having a shoulder thereon against which an edge of the electro may engage, a plurality of independently movable clamp members 10 movable toward and away from said shoulder, spring means normally urging the clamp members independently of each other in the direction of said shoulder, a single manually movable member, and connections between 15 said clamp members and said manually movable member whereby to effect operation of said clamp members collectively by manipulation of said single manually movable member, said connections including means allowing movement of one clamp member to clamping position after another clamp member has reached clamping position.

3. In a quick-change electro-holder for printing machines, an electro-supporting plate having a flat surface upon which the electro may rest, said supporting plate also having a shoulder thereon against which an edge of the electro may engage, a plurality of independently movable clamp members 20 movable toward and away from said shoulder, spring means normally urging the clamp members independently of each other in the direction of said shoulder, a single manually movable member, and connections between 25 said clamp members and said manually movable member whereby to effect operation of said clamp members collectively by manipulation of said single manually movable member, said connections including means allowing movement of one clamp member to clamping position after another clamp member has reached clamping position.

4. In a quick-change electro-holder for printing machines, an electro-supporting plate having a flat surface upon which the electro may rest, said supporting plate also having a shoulder thereon against which an edge of the electro may engage, a plurality of independently movable clamp members 50 movable toward and away from said shoulder, spring means normally urging the clamp members independently of each other in the direction of said shoulder, a single manually movable member, and connections between 55 said clamp members and said manually movable member whereby to effect operation of said clamp members collectively by manipulation of said single manually movable member, said connections including means allowing movement of one clamp member to clamping position after another clamp member has reached clamping position.

having a slot therein extending longitudinally in the direction of movement of the clamp members and other parts movable with the manually movable member and having portions engaging within the slots of the first 70 parts whereby to allow movement of one clamp member to clamping position after another clamp member has reached clamping position.

In testimony whereof I affix my signature. 75
EMIL L. MUELLER.
